UNITED STATES PATENT OFFICE.

SIMON POLLAK, OF PRAGUE, AUSTRIA-HUNGARY, ASSIGNOR TO EMIL FRIEDHEIM, OF NEW YORK, N. Y.

ANTI-INDUCTIVE DEVICE FOR TELEPHONES.

SPECIFICATION forming part of Letters Patent No. 477,870, dated June 28, 1892.

Application filed November 11, 1891. Serial No. 411,549. (No model.) Patented in Germany November 12, 1890, No. 58,513.

To all whom it may concern:

Be it known that I, SIMON POLLAK, a resident of the city of Prague, in the Empire of Austria-Hungary, have invented a certain new and Improved Apparatus for Obviating Induced Currents in Telephones, of which the following is a specification, and for which I have obtained Letters Patent in Germany, No. 58,513, dated November 12, 1890.

10 One of the evils of telephony is the intermingling of noises created by induction when the voices of several speakers become audible. This induction is supposed to be due to the necessary parallelism of conductors which 15 run close together, but to different stations; but it is mainly due to the action of the microphones at the central station and at the end stations.

20 The aim of my invention is to enable any one using a telephone to prevent these induction noises and to regulate the instrument from time to time to overcome the effects of stronger currents or noises.

25 In the drawings, Figure 1 is a diagram illustrating the principle of the invention. Fig. 2 is a plan view of my apparatus; Fig. 3, a plan view of same without the cover. Fig. 4 is a longitudinal section of same.

30 The principle underlying my invention is the following: If an induction-coil S, placed in the line-circuit and receiving an induced current, Fig. 1, is gradually brought nearer to a second coil S', which is merely connected with the telephone-receiver T, and whose 35 windings are parallel to those on S, then a strong induction noise will be noticed in the telephone. If S remains in its position and S' is turned, as by dotted lines in Fig. 1, it will be noticed that the noise in the telephone gradually diminishes, and as soon as 40 the coil S' occupies a position at right angles with its original position not the slightest noise will be noticed in the telephone; but as soon as the coil S' is turned beyond ninety 45 degrees or back the noise will gradually reappear. The weaker the induction noise the sooner it will disappear when the coil S' is turned. If an apparatus of this kind is inserted in a telephone-circuit, as in Fig. 1, 50 then if induction noises are noticed at the receiving-station they will, by turning the

coil S' or sliding the coil S, or both, be entirely suppressed and still leave the main or direct conversation audible.

The apparatus shown in the accompanying 55 drawings is constructed on the principle represented in Fig. 1, and mainly shows a sliding and also a pivoted coil, both placed in proximity to one another and within the reach of the receiver of a telephonic message. 60

S is a coil placed on a drawer or slide s within a box A. S' is another coil suspended from a rod o or other pivot, so that it can be turned by turning the handle K. The wires a b connect the telephonic receiver with the 65 coil S', but are not in a battery-circuit, the receiver having only an induced current from the coil S through the coil S', and this induction-current can be varied in intensity by either turning the coil S' on its pivots or reciprocating the coil S on the slide s, as heretofore described. The line-wires c d connect the coil S with the transmitter and the earth, as in Fig. 1. If coils with primary and secondary wires are used, the ends of the primary 75 wire must remain unconnected. The rod o may be screwed into the box A or its cover to be capable, also, of lifting or lowering the coil S'.

The wires d b may be directly connected by 80 a removable plug e, so that the above apparatus can be cut out when there are no objectionable noises by leaving the plug in place; but as soon as the noises appear the plug e is removed and the coils S S' are thrown into 85 action.

In case the induction noises are objectionable, the coil S' is turned until the noises disappear entirely, or substantially so. Then a microphone-battery may be inserted to 90 strengthen the direct current.

Having described my invention, what I claim, and desire to secure by Letters Patent, is—

1. The combination, with a telephone-transmitter on a line-circuit provided with an induction-coil, of a telephone-receiver adapted to receive and be operated by an induction-current, and an induction-coil on said telephone-receiver circuit adapted and arranged 95 to receive an induction-current from the coil on the line-circuit and transmit the same to 100

the receiver, one of said coils being adjustable as to its distance from the other, substantially as described, and for the purposes set forth.

5 2. The combination, with a telephone-receiver and its coil S' on an induction-circuit connected with said receiver, a telephone-transmitter on a line-circuit, and a coil S on said line-circuit, both said coils being mov-

able and adapted and arranged to be brought into and out of alignment with each other to any desired degree, substantially as described, and for the purposes set forth.

SIMON POLLAK.
